HIS ATTORNEY

UNITED STATES PATENT OFFICE.

JOHN P. STEPP, OF BROOKLYN, ASSIGNOR TO HAFF & WALBRIDGE, OF NEW YORK, N. Y.

PARCEL-CARRIER.

SPECIFICATION forming part of Letters Patent No. 451,627, dated May 5, 1891.

Application filed October 15, 1890. Serial No. 363,216. (No model.)

To all whom it may concern:

Be it known that I, JOHN P. STEPP, of Brooklyn, Kings county, and State of New York, have invented a certain new and useful Improvement in Book-Straps and Like Articles, of which the following is a specification.

This improvement relates to book-straps, shawl-straps, and like articles, which consist, essentially, of a frame, a windlass mounted to rotate within the frame, straps wound upon the windlass and passing through the frame, and a locking device for fastening the windlass in any particular position.

15 My improvement consists in a novel locking device for securing the windlass in position.

In the accompanying drawings, Figure 1 is a side view of a book-strap embodying my improvement. Fig. 2 is an end view with certain parts broken away. Fig. 3 is a view like Fig. 2, showing the locking device in a different position.

25 Similar letters of reference designate corresponding parts in all the figures.

It will be seen that the locking-lever is free to turn at right angles to its locking position. This is convenient when the articles are packed several in a box for shipment, as 30 the projecting handle can be turned in a position to obviate the necessity of using a wide box.

A designates a frame, which preferably will be made of metal with a straight main 35 portion *a* and upturned parallel end portions *a'* *a''*.

B designates a windlass supported between the upturned end portions *a'* *a''* of the frame A. It may consist of a metal shaft *b'* and a 40 wooden hand-piece *b''*, surrounding said shaft. The shaft may be made polygonal, so as to interlock with the hand-piece and prevent the latter from moving independently of it. The end of the shaft, which is journaled in 45 the upturned end portion *a'* of the frame A, is rounded to turn easily in a bearing formed in said end portion of the frame. The other end is, however, polygonal where it passes

through the end portion *a''* of the frame A and is not supported in the latter. The extremity of this end of the shaft is rounded beyond the end portion *a''* of the frame A, and is fitted into a bearing formed in a piece 50 *a''*, which is fastened by rivets *a''* or otherwise to the end portion *a''*.

55 C designates a locking device consisting of a lever which, as here shown, is fulcrumed between its ends to one of the rivets *a''*, whereby the piece *a''* is secured to the end portion *a''* of the frame A. One end is provided with a notch *a''*, which, when the lever is swung into one position, is adapted to engage with the polygonal portion of the windlass and lock the same against movement in either direction. The other end of 60 the lever extends beyond the frame A and forms a handle whereby the lever may be manipulated.

65 The hand-piece *b''* of the windlass is considerably shorter than the distance between the end portions of the frame S, and is so fastened on its shaft *b'* as to leave beyond it portions of the shaft upon which straps D may be wound. These straps are of ordinary or any suitable form, are attached to 70 the shaft *b'* of the windlass beyond the hand-piece *b''* of the windlass, and pass thence through slots in the main portion *a* of the frame A. Beyond the latter they are provided with rings or eyes *d'* *d''*. The straps 75 may be wound upon and unwound from the windlass and the entire device used in the ordinary way.

80 By my improvement I produce a very simple, inexpensive, and effective locking device.

85 What I claim as my invention, and desire to secure by Letters Patent, is—

90 The combination, with a frame having a main portion and upturned parallel end portions, of a windlass journaled in one of the upturned end portions and passing loosely through the other upturned end portion of the frame, a piece fastened to the last-mentioned upturned end portion of the frame 95 and provided with a journal for the windlass-

shaft, and a swinging locking-lever fulcrumed between the last-mentioned upturned end portion of the frame and the piece fastened thereto, the said lever being notched to engage with the shaft of the windlass and free to turn at right angles to its locking position, substantially as specified.

In testimony whereof I have signed my name to this specification in the presence of two subscribing witnesses.

JNO. P. STEPP.
